UNITED STATES PATENT OFFICE.

COVELLE S. McELROY, OF STEPPVILLE, KANSAS.

ATTACHMENT FOR SCREEN-DOORS.

No. 873,580.

Specification of Letters Patent.

Patented Dec. 10, 1907.

Application filed June 8, 1907. Serial No. 378,037.

To all whom it may concern:

Be it known that I, COVELLE S. McELROY, a citizen of the United States, residing at Steppville, in the county of Cherokee and 5 State of Kansas, have invented new and useful Improvements in Attachments for Screen-Doors, of which the following is a specification.

This invention relates to screen doors that 10 are used for excluding flies and other insects; and it has for its object to provide a screen door attachment, which when the door is opened to permit of the passage of persons will constitute a guard to prevent 15 flies and other insects from entering the room over the top of the door.

Further objects of the invention are to simplify and improve the construction and operation of this class of devices.

20 With these and other ends in view which will readily appear as the nature of the invention is better understood, the same consists essentially in a foldable guard adapted to be applied to the top of the door and to 25 the lintel of the door frame in such a manner that when the door swings open the guard will be unfolded; said guard being composed of a plurality of ribs, means for movably sustaining said ribs in position, and a 30 flexible member, preferably of textile material, connected with and supported by the ribs.

The invention further consists in the improved construction and novel arrangement 35 and combination of parts which will be hereinafter fully described and particularly pointed out in the claims.

In the accompanying drawings, has been 40 illustrated a simple and preferred form of the invention; it being, however, understood that no limitation is necessarily made to the precise structural details therein exhibited, but that changes, alterations and modifications within the scope of the invention may 45 be resorted to when desired.

In the drawing, Figure 1 is a perspective view showing the upper portion of a door frame to which the invention has been applied in position for operation. Fig. 2 is a 50 horizontal sectional view showing the door swung open and the improved guard unfolded. Fig. 3 is a horizontal sectional view showing the door closed and the guard in a folded position.

55 Corresponding parts in the several figures are denoted by like characters of reference

The lintel 1 of the door frame F is preferably provided with a recess 2 in the underside thereof for the purpose of accommodating the improved attachment. The latter 60 comprises a rod or arm 3, one end of which is bent to form an eye 4 and a segmental bracket 5, which latter is concentric with the eye 4. The arm or rod 3 is secured in the recess 2 of the lintel, adjacent to the hinged 65 edge of the door 6 by means of a pivotal member such as a pin 7 extending through the eye 4. The rod or arm 3 is connected with the door, adjacent to the upper edge of the latter, by means of a sleeve or keeper 70 8 in which said rod or arms has a limited sliding movement when the door is swung open or shut.

Loosely connected with the concentric bracket 5 are a plurality of radial ribs 9; said 75 ribs being provided with loops or eyes 10 engaging said bracket. These ribs are sustained in an approximately horizontal position in a plane adjacent to the upper edge of the door by means of a curved supporting 80 bracket 11 which is suitably secured upon the lintel within the recess 2 of the latter; said supporting bracket being extended beyond the lintel a sufficient distance to afford a frame support for the ribs 9. The upper 85 edge of the door has a cut away portion or recess 12 adjacent to the hinged edge for the purpose of accommodating the bracket 11 when the door is closed.

Suitably connected with the ribs 9 is a 90 foldable guard member 13 which may be made of any suitable light textile material; one edge of said guard member is connected with the rod or arm 3, and the other edge is secured upon the lintel, within the recess of 95 the latter by fastening means such as tacks 14.

The operation and advantages of this invention will be readily understood from the foregoing description taken in connection with the drawings hereto annexed. When 100 the door, to which the invention has been applied, is swung open, the rod or arm 3 will be swung outward from the lintel with the door, and the foldable guard will thus be extended, as shown in Fig. 2 of the drawings, so as to 105 prevent flies and other insects from entering over the upper edge of the door; the ribs of the guard being sustained in approximately horizontal position upon the guard bracket 11, and the said ribs being loosely connected 110 with the curved supporting bracket 5, so that the guard may be freely extended; when the

door is shut, the guard will be collapsed, and the ribs will be supported within the recess 2 of the lintel, from which the folds of the flexible guard member 13 will depend, as will 5 be readily understood.

This improved guard appliance may be manufactured at a very moderate expense, and when applied to screen doors it will obviate the serious difficulty heretofore experienced of insects passing into the room over 10 the upper edge of the door.

Having thus fully described the invention, what is claimed as new is: —

1. In a device of the class described, a pivotally supported rod or arm having a supporting bracket concentric with the pivot, a plurality of ribs pivoted upon said bracket, a flexible guard member connected with the arm and ribs, and supporting means for the 20 latter.

2. In a device of the class described, a pivotally supported rod or arm having a supporting bracket, a plurality of ribs pivoted upon said bracket, means for supporting the ribs 25 in approximately horizontal position, and a foldable guard connected with the ribs and with the rod or arm.

3. A door lintel, a rod pivoted upon the underside thereof and having a supporting 30 bracket concentric with the pivot, a plural-

ity of ribs pivoted upon said bracket, supporting means secured upon the lintel for supporting said ribs in approximately horizontal position, a door, means for securing the rod or arm slidably upon the door, and a 35 flexible foldable guard member connected with the ribs at one edge upon the lintel and at the other edge upon the pivoted rod or arm.

4. A door lintel having a recess in its underside, a rod or arm pivoted in said recess and having a bracket concentric with the pivot, a plurality of ribs loosely mounted upon said bracket, a supporting member secured upon the lintel and engaging the ribs 45 to support the latter in approximately horizontal position, a door having a recess at its upper edge to accommodate the supporting member, means for connecting the pivoted rod or arm slidably with the door, and the 50 flexible guard member carried by the ribs and having one edge connected with the pivoted rod or arm and the other edge secured in the recess of the lintel.

In testimony whereof, I affix my signature 55 in presence of two witnesses.

COVELLE S. McELROY.
